ATTORNEY

UNITED STATES PATENT OFFICE.

WILLIAM B. STRINGER, OF CLEBUENE, TEXAS.

STAND.

Application filed May 25, 1927. Serial No. 194,215.

This invention relates to a display stand for vegetables and the like, the general object of the invention being to provide a plurality of trays having transparent fronts for holding 5 the vegetables on display, with a stand in which the trays are supported and with means for forming an ice chamber in the stand to keep the vegetables or other articles in the trays cool.

Another object of the invention is to make 10 the stand rotatable so that the various trays can be brought to a position where the articles can be taken therefrom.

This invention also consists in certain other 15 features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several 20 views, and in which:—

Figure 1 is a side view of the device.

Figure 2 is a top plan view thereof.

Figure 3 is a section on line 3—3 of Figure 2.

Figure 4 is a section on line 4—4 of Figure 3.

In these views, 1 indicates an upright which 30 is supported by a base 2 and which has secured to its lower part a supporting disk 3 which has a race therein for the balls 4. The bottom 5 of the tray supporting cabinet A has a race in its lower face to receive portions of the balls 4, and this bottom is connected by the strips 6 35 with the top piece 7 of the cabinet. This top piece is of smaller diameter than the bottom piece 5 and the strips are convergently arranged from the bottom piece to the top piece.

These strips 6 are spaced apart as shown, and 40 they divide the cabinet into compartments, each of which receives a tray 8 which has its bottom resting on the bottom piece 5 and its top engaging the top piece 7. The front and rear of each tray slopes upwardly and inwardly to conform to the shape of the cabinet. Each tray also has its side walls convergently arranged with its front wider than its rear, the 45 front fitting snugly in the space formed by the strips, and as each pair of strips are wider apart at their lower ends than at their upper ends, the tray is made wider at its lower part than at its top part. A door 9, composed of a

frame and a transparent member 10, covers 50 the open front of each tray and each door is hinged to one of the strips 6, so that access can

be had to the tray by opening said door. The tray can also be removed from the cabinet through the door opening formed by the space between the two strips. 60

The rear portions of the trays abut, as clearly shown in Figure 4, so that the rear portions of the trays form an interior chamber 11 in the center of the cabinet through which the post or upright 1 passes. 65

A substantially annular ice receiving casing 12 having its circumferential part open is placed in the lower part of the chamber and has an inwardly sloping bottom which rests on an inwardly sloping base 13 placed upon the bottom piece 5. The casing 12 is provided with a central opening 14 through which the upright 1 passes and a spout 15 is arranged in the inner wall of the casing 12 for draining the water from the melting ice 70 therefrom. This water will pass through the openings in the base 13 and bottom piece 5 through which the upright 1 passes and will drain through a port 16 formed in the disk 3. Vent holes 17 are formed in the top piece 7. 75 By making the ice receiving casing with an open outer part, which is closed by the rear ends of the trays, the ice and cold air in the ice receiving casing acts directly on the rear portions of the trays so that the maximum 80 cooling effect is secured.

From the foregoing it will be seen that 85 vegetables and the like can be placed in the trays and customers can see the articles by looking through the transparent portions of the doors so that they may make their selections without touching the articles. The articles will be kept fresh by means of the cooling effect of the ice placed in the casing 12, which causes the air in the said casing and in the 90 chamber 11 to become cool and as this air is in contact with the rear walls of the trays, the articles in the trays will be kept chilled. The cabinet can be turned on the disk 3 so that 95 all the trays can be brought into view without the customer walking around the cabinet. 100

It is thought from the foregoing description that the advantages and novel features of my invention will be readily apparent.

I desire it to be understood that I may make 105 changes in the construction and in the combination and arrangement of the several parts, provided that such changes fall within the scope of the appended claims.

What I claim is:—

1. A display stand of the class described comprising an upright, a cabinet rotatably

mounted thereon, said cabinet comprising a bottom piece, a top piece and spaced strips connecting the two pieces together, trays removably arranged in the spaces between the strips and resting upon the bottom piece, doors having transparent portions hingedly connected with the strips for closing the fronts of the trays and permitting removal of the trays, the inner walls of the trays forming a central chamber in the cabinet and an ice receiving casing located in said chamber and having an outer circumferential opening therein which is closed by portions of the rear parts of the trays.

10 15 2. A display stand of the class described comprising an upright, a cabinet rotatably mounted thereon, said cabinet comprising a bottom piece, a top piece of smaller diameter

than the bottom piece, spaced strips connecting the peripheries of the two pieces together, 20 the strips being convergently arranged from the bottom piece to the top piece, doors having transparent portions hingedly connected with the strips, trays removably arranged in the spaces formed by the strips, each tray having 25 its front and rear sloping inwardly and upwardly and inwardly and inwardly, the rear corners of the trays abutting, the rear portions of the trays forming a central chamber and an ice receiving casing arranged in said chamber and having an opening in its center through which the up-right passes.

In testimony whereof I affix my signature.

WILLIAM B. STRINGER.
